OPERATING MECHANISM

David C. Prince, Swarthmore, Pa., assignor to
 General Electric Company, a corporation of
 New York

Application October 19, 1934, Serial No. 749,056

4 Claims. (Cl. 123—24)

My invention relates to operating mechanisms, more particularly to mechanisms employing an explosive charge as the actuating means, and has for its principal object the provision of an improved operating mechanism of the aforesaid type which shall be positive and efficient in operation and simple, compact and inexpensive in construction.

Certain operations, as closing of a large electric circuit breaker for example, require the application of considerable force throughout a short distance and over a very short period of time. Heretofore the closing mechanisms of oil circuit breakers, such as solenoids, motor mechanisms, etc. have assumed a considerable part of the breaker cost as compared with the amount of time that the mechanisms are in use. A simple and inexpensive operating mechanism which is capable of efficiently applying adequate closing force is, therefore, highly desirable.

In accordance with my invention, the size and cost of the operating mechanism are appreciably reduced by using an explosive charge as a slow burning powder, for the actuating means. The mechanism is adapted for a plurality of automatic operations by means of a firing device which is automatically reset in response to operation of said mechanism.

My invention will be more fully set forth in the following description referring to the accompanying drawing, and the features of novelty which characterize my invention will be pointed out with particularity in the claims annexed to and forming a part of this specification.

Referring to the drawing, Fig. 1 is a view, partly diagrammatic and partly in section, of an operating mechanism embodying my invention and Fig. 2 illustrates the application of the aforesaid mechanism to an electric circuit breaker.

The operating mechanism illustrated by Fig. 1 may be of general application where a limited number of operations are desired without servicing of the mechanism. The mechanism comprises a suitable pressure resisting casing 1 and a plunger or piston 2 which is mounted and guided in the upper wall of the casing for reciprocal movement. The casing 1 has mounted therein a cartridge receiving block 3 for retaining a plurality of cartridges 4. A detachable cap 5 normally closes the lower end of the casing.

The cartridge 4 may be of any suitable form and in the present instance comprises a casing 6 containing an explosive charge 7, as a suitable slow burning powder. The explosive charge 7 is ignited electrically, as by a fusible or heating

element 8 energized in a manner hereinafter described. The cartridge 4, which is inserted within a bore 9 from the lower side of the block 3, may be removed after discharge and replaced by another cartridge through the lower end of the 5 casing by reason of the detachable cover 5.

A plurality of cartridges 4 are mounted within the block 3 and are individually fired by means of a separate firing device 10 which is operatively connected to the piston 2 so as to place a fresh 10 cartridge in readiness for a subsequent operation. The firing circuit for each cartridge includes a source of potential as a battery 11 which is connected at one terminal through a conductor 12 to the metallic casing 1, and at the other terminal through a control switch 13 and firing device 10 15 to the cartridge.

Closing of a particular cartridge circuit causes current to flow from the battery 11 through switch 13, firing device 10, and cartridge heating 20 element 8 which is electrically connected to the metallic casing 1 through the metallic cartridge casing 6 and block 3, to cause firing of the cartridge and upward movement of the actuating piston 2. 25

Referring more particularly to the electrical connections, the firing device 10 comprises a switch arm 14 which is mounted on a rotatable shaft 15 for coacting with a plurality of radially disposed contacts 16. Connected to the shaft 15 30 is a ratchet wheel 17 which is operatively connected to the piston 2 through a lever 18 and pawl 19, the arrangement being such that each descending or return stroke of the piston 2 causes counter-clockwise rotation of the ratchet 35 wheel 17 one notch so as to move the switch arm 14 out of engagement with one contact 16 and into engagement with the next contact.

The pawl lever 18 is pivotally connected at one end to a sleeve 20 secured to the piston 2 40 and at its other end to the pawl 19, an extension 21 of the casing 1 providing a lost motion pivotal mounting at 22. The pawl 19 is maintained in operative position with respect to the wheel 17, as by a tension spring 24 tending to bias the pawl 45 in clockwise direction. Accordingly, after a working and return stroke of the piston 2 the pawl 19 is in readiness, as illustrated, for a subsequent actuation of the firing device 10.

The control switch 13 comprises a simple snap 50 switch having an over center spring 25 and a pivoted switch arm 26 adapted to make momentary contact at 27. The contact 27 is electrically connected to the switch arm 14 as by contact 28 engaging a conducting collar 29 which is elec- 55

trically connected to the switch arm 14 and insulated with respect to the shaft 15. Each contact 16 is separately connected to a corresponding terminal 30 mounted in the bottom of detachable cap 5. Each terminal 30 comprises a conducting member as a pin 31 extending through and insulated with respect to the cap 5, as at 32, and adapted to make electrical contact with the corresponding cartridge terminal 33. The cartridge terminal 33 is insulated at 34 with respect to the metallic cartridge casing and is electrically connected at 35 to one terminal of the cartridge firing element 8, the other terminal being connected at 36 to the cartridge casing.

15 The operation of the device is initiated by actuation of the snap-over control switch 13. The momentary contact establishes a circuit through the firing device 10 and one of the cartridges within the casing, resulting in ignition of the powder charge, generation of pressure within the casing and projection of the piston 2 upwardly. The piston 2 is suitably provided with means, as a slot 2', for permitting exhaust of the gases and products of combustion from the casing 1 when the piston is at or near the end of its working stroke. Accordingly, the operating piston 2 is acted on by a comparatively large and positive force throughout its short stroke.

As previously described, a working stroke of 30 the piston 2 moves the pawl 19 beneath the next ratchet tooth so that the return stroke rotates the ratchet wheel 17 one notch in a counter-clockwise direction to move the switch arm 14 into contact with the next contact 16. With this arrangement a cartridge cannot be fired by the control switch unless the piston 2 is in the proper position to deliver a working stroke.

40 Operation of control switch 13 again fires the cartridge associated with the newly established circuit, the above described cycle being repeated until the switch arm 14 has made a revolution. It will, of course, be apparent that suitable indicating or signal means may be associated with the firing device 10 to indicate that a new supply 45 of cartridges is required.

It will be noted that the comparatively massive part of the mechanism, namely the casing, cartridge block, etc., is stationary and that the movable elements of the firing device 10 may be 50 designed so as to involve very little inertia and to occupy very small space. This feature is an important cost consideration since comparatively expensive revolver devices for the cartridges are avoided. Furthermore, the control switch 13 55 lends the mechanism to remote control operation.

Fig. 2 illustrates the application of my improved operating mechanism to a large capacity oil circuit breaker. The circuit breaker generally indicated at 40 comprises stationary contact structure 41 mounted at the lower ends of lead-in bushings 42 and a movable conducting bridging member 43. The contact structure is normally oil immersed within a casing (not shown). The breaker is illustrated in the open circuit position, closing of the circuit being effected by raising of the bridging member 43 by the operating or lift-rod 44 so as to engage and interconnect the stationary contacts 41.

70 The circuit breaker lift-rod 44 is operatively connected to the piston 2 of the operating mechanism through suitable force-transmitting linkage. In the present instance a bellcrank 45 pivotally mounted at 46 is actuated by the piston 2 in counter-clockwise direction to cause closing of the breaker. One arm of the bellcrank 45 is con-

nected at 47 through a linkage 48 to an operating lever 49. The lever 49 is connected at 50 to a linkage 51 for causing substantially reciprocal movement of the rod 44 in response to rotation of the lever 49. The other arm of the bellcrank 45 is connected at 52 to a collapsible restraining linkage 53 which coacts with a tripping solenoid 54. The solenoid 54 may be associated with the usual current transformer 55 so that the tripping linkage 53 is tripped by the solenoid 24 in response to excess current. Tripping or collapse of the linkage 53, as will be apparent, permits the bellcrank 45 to rotate clockwise to the open circuit position shown.

Closing of the circuit breaker by the operating mechanism is effected by the aforesaid firing operation and upward movement of the piston 2 which engages a roller 56 carried by the bellcrank 45. The resulting counter-clockwise rotation of the bellcrank 45 transmits clockwise movement to the lever 49 resulting in raising of the bridging member 43 and closing of the breaker. For the purpose of permitting operation of the mechanism only when the circuit breaker is in open circuit position, an auxiliary switch 45' operatively connected to the bellcrank 45 is included in the circuit 12. This switch is closed only when the circuit breaker is open.

It will be apparent that the amount and character of the explosive charge may be chosen to suit the particular operating requirements of the mechanism. For example, slow burning powders which are well known in the art may produce a positive and effective closing operation comparable to that produced by strong compression springs and solenoids without excessive shock or impact. The operating characteristics of the mechanism are furthermore particularly suited to closing of large circuit breakers, as compared with solenoids, since the circuit breaker mechanism resistance is comparatively large at and near the end of the closing stroke. An operating mechanism as above described therefore operates very efficiently under such conditions since a large operating force is available throughout the working stroke.

It should be understood that my invention is not limited to specific details of construction and arrangement thereof herein illustrated, and that changes and modifications may occur to one skilled in the art without departing from the spirit of my invention.

What I claim as new and desire to secure by Letters Patent of the United States, is:

1. Operating mechanism comprising a casing forming a pressure chamber, a piston operable in said chamber, means for generating pressure for actuating said piston including a plurality of normally stationary explosive charges in said chamber, a source of electric potential, a circuit controlling device operatively connected to said piston for connecting a fresh charge to said potential in response to actuation of said piston, and a control switch for completing the firing circuit of said charge.

2. Operating mechanism comprising a casing forming a pressure chamber, a piston operable in said chamber, a plurality of normally stationary explosive charges in said chamber, a source of electric potential, a circuit controlling device having a plurality of contacts individually connected to said charges, means including a pawl and ratchet operatively connected to said piston for successively connecting said potential to each of said

charges, and a control switch for completing the charge firing circuit.

3. In a circuit breaker closing system including a circuit breaker having a force-transmitting linkage, means for actuating said linkage comprising a casing forming a pressure chamber, a piston operable in said chamber and adapted to engage said linkage, means for generating pressure for actuating said piston including a plurality 5 of stationary explosive charges, a circuit controller operatively connected to said piston for establishing a firing connection with a fresh charge in response to a circuit closing operation, and a remote control switch for completing the firing 10 circuit of said charge.

4. In a circuit breaker closing system including a circuit breaker having a force-transmitting linkage, means for actuating said linkage comprising a casing forming a pressure chamber, a piston operable in said chamber and adapted to engage 5 said linkage, means for generating pressure for actuating said piston including a plurality of explosive charges, an auxiliary switch operatively connected to said linkage, a circuit controller in series with said auxiliary switch operatively connected to said piston for establishing a firing connection with a fresh charge in response to a circuit closing operation, and means for completing 10 the firing circuit of said charge.
